UNITED STATES PATENT OFFICE.

BERTHA CLARK, OF NEW YORK, N. Y.

DRAW-STRING

1,091,294.

Specification of Letters Patent. Patented Mar. 24, 1914.

Application filed August 1, 1913. Serial No. 782,433.

To all whom it may concern:

Be it known that I, BERTHA CLARK, a citizen of the United States, and a resident of the city of New York, borough of Brooklyn, in the county of Kings and State of New York, have invented a new and Improved Draw-String, of which the following is a full, clear, and exact description.

The object of the invention is to provide a new and improved draw string or band designed for use in the hem of the gathered waistband of a washable garment and arranged to allow of conveniently and quickly removing the draw string or band prior to washing the garment and to permit the ready insertion of the draw string or band after the garment is washed.

In order to produce the desired result use is made of a drawstring provided at the ends 20 with buttons adapted to engage buttonholes in the garment on which the draw string is used, one of the said buttons having a loop adapted to engage the other button.

A practical embodiment of the invention is represented in the accompanying drawings forming a part of this specification, in which similar characters of reference indicate corresponding parts in all the views.

Figure 1 is a perspective view of a skirt 30 provided with the improvement, the placket of the skirt being open and the band being shown in position for insertion into the hem; Fig. 2 is a similar view of the same with the band in position in the hem and with the 35 flaps open; Fig. 3 is a like view of the same with the parts in closed position and the outer flap turned back; Fig. 4 is an enlarged sectional plan view of the improvement; Fig. 5 is an enlarged face view of the band 40 button and hook; Fig. 6 is a plan view of the same; Fig. 7 is a face view of the band buckle and button; and Fig. 8 is a plan view of the same.

The skirt is provided with the usual waistband A, and overlapping opening and closing flaps B and C, and with a hem D extending along the waistband A. The ends of the hem D terminate short distances from the opening and closing flaps B and C, and buttonholes E and E' are provided at the ends 45 of the waistband A adjacent the opening and closing flaps B and C. In the hem D is removable held a band F preferably of an elastic material and provided at one end 50 with a combination buckle G and button G', made in one piece, of which the buckle is

adjustable on the end of the band F while the button G' is adapted to engage the buttonhole E to fasten this end of the band in place on the waistband. The other end of 60 the band F is provided with a combination loop H, button H' and attaching loop H², on which latter this end of the band F is fastened. The loop H is adapted to be hooked onto the button G' after the latter has been 65 passed through the buttonhole E, and the button H' is adapted to engage the buttonhole E' so that the flaps B and C are fastened together and at the same time the ends of the band F are removably fastened to the 70 ends of the waistband of the garment. By the arrangement described the ends of the band F are removably secured to the ends of the waistband A by the use of the buttons G' and H' and the buttonholes E, E', it being understood that whenever it is desired 75 to wash the garment the buttons G', H' are disengaged from the buttonholes E, E' to allow of pulling the band F out of the hem D. After the garment has been washed 80 the band F is reinserted in the hem D and for this purpose the loop H is used for pushing the bands through the hem D, as indicated in Fig. 1, the said loop serving as a needle usually employed for drawing a band 85 through a hem. After the band has been reinserted the button G' is engaged with the buttonhole E and the button H' is engaged with the buttonhole E' and then the loop H is hooked onto the outer end of the button 90 G' so that the flaps B and C are held locked in closed position.

By using the elastic band F the waistband A and the hem D are held in gathered position during the time the flaps are open and while the elastic band F is in contracted condition. When the garment is closed the elastic band F is expanded around the waist 95 of the wearer to insure snug fitting of the waistband A on the waist of the wearer. By providing the buckle G the elastic band F can be lengthened or shortened to suit different sized waists.

Having thus described my invention, I claim as new and desire to secure by Letters 100 Patent:

1. A drawstring adapted to be inserted in the hem of a garment, buttons on the ends of said string adapted to engage buttonholes in said garment, one of said buttons having a 110 loop adapted to engage the other button.

2. A draw string adapted to be inserted in

the hem of a garment, a combined buckle and button adjustably held on one end of the draw string, and a combined button and loop held on the other end of the draw string, the said loop being adapted to engage the said buckle button and the said buttons being adapted to engage buttonholes in said garment.

In testimony whereof I have signed my name to this specification in the presence of 10 two subscribing witnesses.

BERTHA CLARK.
